UNITED STATES PATENT OFFICE.

ARTHUR J. OTTO, OF MILWAUKEE, WISCONSIN, ASSIGNOR TO JOHNSON SERVICE COMPANY, OF MILWAUKEE, WISCONSIN, A CORPORATION OF WISCONSIN.

THERMOSTAT.

Application filed June 18, 1923. Serial No. 646,091.

To all whom it may concern:

Be it known that I, ARTHUR J. OTTO, a citizen of the United States, residing at Milwaukee, in the county of Milwaukee and State of Wisconsin, have invented certain new and useful Improvements in Thermostats, of which the following is a specification.

The present invention relates to automatic control of atmospheric conditions such as temperature, humidity and the like, and resides in certain structural improvements in automatic control devices of the pressure operated relay type.

15 The chief object of the invention is to produce a compact device of simple and inexpensive construction, capable of precise and certain operation and constructed of metal throughout so as to avoid packed joints and 20 leather and fabric diaphragms heretofore commonly used in this art.

The preferred embodiment of the invention is illustrated in the accompanying drawings, in which—

25 Fig. 1 is a front elevation of the device with parts broken away to show the internal construction;

30 Fig. 2 is a vertical sectional view, different portions of the device being sectioned on different planes so as to illustrate various of the ports and chambers;

Fig. 3 is a section on the line 3—3 of Fig. 1;

35 Fig. 4 is a section on the line 4—4 of Fig. 1.

In the drawings the usual cover or casting is omitted as it forms no part of the invention.

The body 6 of the instrument consists of a 40 casting formed with certain ports and chambers hereinafter described in detail. The general form is subject to some variation, but that illustrated in the drawing is preferred because it is compact and because the 45 ports can be easily formed by drilling.

The front of the body 6 is provided with a cover 7 which is held in place by screws in the usual manner. The joint between the cover 7 and the body 6 is sealed by means of 50 an interposed gasket 8 and this gasket is provided with apertures which register with the communicating ports in the body 6 and cover 7. The cover 7 closes the front

face of the relay motor chamber 9 formed in the body 6.

55 The body 6 is formed with a seat 10 designed to fit and seal against a pipe head fitting familiar to those skilled in the art, and not shown in the drawings. This fitting is mounted in the wall of the room whose temperature or humidity is to be regulated, and the pipes which supply air or other pressure fluid to the device and which connect the device to the motor to be controlled are permanently connected to this pipe head. By 60 this construction the body 6 is properly connected to the pipes by merely mounting it on the pipe head.

To effect this result, the seat 10 is formed with a supply recess 11 from which the supply ports lead. One of these, the main motor supply port, is indicated at 12 and leads to the main inlet valve chamber 13. The main inlet valve 14 is mounted in this chamber and seats in the direction of flow to the 75 relay motor chamber 9. The valve 14 is guided by a combined valve guide and spring seat 15 which is threaded into the valve chamber 13 from the rear of the body 6, and which is provided with a sealing 80 flange so as to make a fluid tight joint with the body. A spring 16 confined between the member 15 and the valve 14 urges the valve in a closed direction. It will be observed that a portion of the valve projects 85 into the relay motor chamber 9 far enough to be engaged by a plate or lever actuator hereinafter described.

Also leading from the supply recess 11 is a relay supply port 17 which discharges 90 past a restricting needle valve 18 into a continuing port 20 also formed in the body 6. The needle valve 18 is threaded into an aperture in the body 6 and leakage is prevented by a sealing plug 19 in the usual 95 manner.

The port 20 in the body 6 leads through an aperture in the gasket 8 to a port 21 formed in the cover 7. This port extends across the cover and has at the center of 100 the cover a branch 22 which leads to the diaphragm chamber 23. This diaphragm chamber is enclosed by a flexible front wall 24 and a flexible rear wall 25 composed of light sheet metal formed with annular corrugations. 105 The front wall and rear wall are connected

together at their peripheries by brazing or soldering and the front wall is sealed to the cover 7 around the port 22 by means of a lock ring 26. This joint is further sealed 5 by soldering.

The port 21 also communicates with an extension port 27 formed in the body 6 through another registering aperture formed in the gasket 8. The port 27 terminates in a chamber into which is screwed a leak tube 28 provided with the usual minute leak port in its end. This leak port is controlled by a transparent celluloid valve 29 which is carried by a responsive element 10 30 in the usual manner and which is so moved by the response of the element 30 to changes in atmospheric condition as to seat against the end of the leak tube or move more or less far from the same, thus producing a variable throttling effect on the outflow through the leak port.

In the use of the device the needle valve 18 is so adjusted that the flow past it is less than the capacity of the port in the leak 25 tube 28. From this it results that the variable throttling of the leak port by the valve 29 produces a variable pressure in the diaphragm chamber 23.

The responsive element 30 is illustrated as 30 consisting of a bi-metallic thermostatic bar. Any other responsive element such, for example, as a hygrostatic element might be substituted and such substitution would commonly involve minor changes in the 35 mounting of the element such as to enable it to produce the desired movement of the valve member 29.

In the example illustrated, the responsive element 30 is mounted on a saddle 31 which 40 is supported by horizontal pivot screws 32 carried by brackets on the body 6. This saddle is urged to rotate on these pivot screws by the springs 33 so as to seat against the end of an auxiliary adjusting screw 34 which serves to fix its position. The screw 34 is threaded through a main adjusting screw 35 which carries an arcuate dial against which reads a combined index and 45 detent spring 37. The auxiliary adjusting screw 34 provides an initial adjustment by which the instrument is zeroed when installed. The user adjusts the response of the instrument from time to time by turning the dial 36 and consequently the screw 50 35. Adjustments so made are indicated on the dial by the index 37 (see Fig. 1).

Communicating with the rear of the relay motor chamber 9 is an exhaust valve chamber 38 formed with an exhaust valve seat 60 39. The exhaust valve 40 seats outward against the seat 39 and is guided by the exhaust valve guide 41 threaded into the inner end of the chamber 38 and provided with ports for the passage of air. The exhaust valve 40 is urged open by the exhaust valve

spring 42 and is provided with a portion which extends through the guide 41 and projects into the relay motor chamber 9.

The exhaust valve spring 42 is weaker than the inlet valve spring 16 and the two 70 valves are actuated through a triangular actuator plate 43 by the movements of the diaphragm member. This plate 43 is suspended loosely on a pin 44 at its top and is provided with a center boss 45 which is engaged by the middle of the rear diaphragm wall 25. Near one of its lower corners the actuator plate 43 seats against the end of the inlet valve 14 and near its other lower corner it seats against the end of the exhaust valve 40. Consequently, the plate is at times subjected to stress exerted on its central boss 45 by the diaphragm and is supported in opposition to this stress at three points, namely: on the pin 44, the 75 valve 14 and the valve 40.

Since the spring 16 is stronger than the spring 42 pressure exerted by the diaphragm on the plate 43 will first close the exhaust valve 40 and then open the inlet valve 14. 90 On reverse movement the inlet valve will close before the exhaust valve is permitted to open, therefore, the device will operate to establish a pressure in the diaphragm motor chamber 9 which follows the pressure 95 created within the diaphragm chamber 23 through the varying throttling action of valve 29 as it is moved by the responsive element 30.

The pressure so created in the chamber 9 is transmitted to the controlled motor by the motor control port 46 which leads from the chamber 9 to a recess 47 in the seat 10. As is understood, the recess 47 communicates with a pipe connection in the pipe head heretofore described, such connection leading to the controlled motor.

The use of relay valves permits the device to feed air rapidly enough to secure prompt 110 response of the controlled device. The use of the reversely seated inlet and exhaust valves in conjunction with the unequal valve springs and the lever plate or equalizing plate 43 produces a simple construction 115 which gives the desired serial action of the inlet and exhaust valves.

It will be observed that all ports are accessible for inspection and repair and that their construction is such as to permit inexpensive manufacture.

What is claimed is:

1. In an automatic control device, the combination of independently movable inlet and exhaust valves, a lever mechanism constructed and arranged to balance an opening stress exerted thereby on one of said valves against a closing stress simultaneously exerted thereby on the other of said valves; resilient means arranged to resist movements of the valves under the stresses exerted there-

- on through said lever mechanism, and to exert a predominant resistance on one of said valves, whereby said valves are caused to open, one at a time, by the lever mechanism in different positions thereof and both valves are closed in an intermediate position; a diaphragm subject on one side to the pressure controlled by said valves, and arranged to actuate said lever mechanism; a responsive element arranged to control a fluid pressure acting against the other side of said diaphragm; and means for subjecting a controlled device to the first named pressure.
2. In an automatic control device, the combination of independently movable inlet and exhaust valves, a lever mechanism constructed and arranged to balance an opening stress exerted thereby on one of said valves against a closing stress simultaneously exerted thereby on the other of said valves; resilient means arranged to resist movements of the valves under the stresses exerted thereon through said lever mechanism, and to exert a predominant resistance on one of said valves, whereby said valves are caused to open, one at a time, by the lever mechanism in different positions thereof and both valves are closed in an intermediate position; a metallic diaphragm motor arranged to actuate said lever mechanism and urged in one direction by the pressure controlled by said valves; a responsive element arranged to control a fluid pressure urging said diaphragm motor in the opposite direction; and means for subjecting a controlled device to the first named pressure.
3. A control device comprising fixed structural parts providing a fluid pressure supply passage and a delivery passage connected by a supply port, and having an exhaust port connecting said delivery passage to atmosphere; valves controlling said supply port and said exhaust port; unequal springs, the dominant spring urging said supply valve closed and the other spring urging said exhaust valve open; a bearing plate loosely engaging said valves and serving when moved in one direction to urge said valves simultaneously in opposition to their springs; an expansible member positioned to engage said plate and move it in the direction aforesaid; means for supplying and exhausting pressure fluid to operate said expansible member; and an element responsive to changes in the medium to be controlled serving to control said supplying and exhausting means.

In testimony whereof I have signed my name to this specification.

ARTHUR J. OTTO.
